UNITED STATES PATENT OFFICE.

THOMAS WATKINS, OF PHILADELPHIA, PENNSYLVANIA.

GAGE-COCK.

No. 894,087.

Specification of Letters Patent.

Patented July 21, 1908.

Application filed August 22, 1907. Serial No. 389,665.

To all whom it may concern:

Be it known that I, THOMAS WATKINS, a citizen of the United States, residing at Philadelphia, county of Philadelphia, and State of Pennsylvania, have invented a certain new and useful Improvement in Gage-Cocks and the Like, of which the following is a specification.

My invention relates to a new and useful improvement in gage cocks and the like, and has for its object to provide an exceedingly simple and efficient device of this description which may be readily attached to a boiler and when so attached will permit the opening and closing of the main valve to test the steam and water by permitting a certain amount thereof to escape as is usual, and which will also permit the removal of the gage cock proper while preventing the escape of steam from the boiler thus providing for the repair of the valve or other parts of the device without the necessity of emptying the boiler of steam or water.

With these ends in view, this invention consists of the details of construction and combination of elements hereinafter set forth and then specifically designated by the claims.

In order that those skilled in the art to which this invention appertains may understand how to make and use the same, I will describe its construction in detail, referring by letter to the accompanying drawing forming a part of this specification, in which—

Figure 1 is a longitudinal section of my improvement. Fig. 2, a section at the line Y—Y of Fig. 1. Fig. 3, a section at the line X—X of Fig. 1.

In carrying out my invention as here embodied, I provide a nipple A which is preferably tapered having the threads B formed thereon by which it is adapted to be screwed through the wall of the boiler. This nipple has a central opening C which communicates with the interior of the boiler and leads to the recess D, a portion of which is threaded as indicated at E for the reception of the inner end of the valve plug F.

G represents the body of the gage cock which is threaded to the outer end of the valve plug and has a central opening I formed therethrough in which is fitted the valve stem J, said stem having formed thereon the valve K adapted to close upon the valve seat L formed at the inner end of the opening I, and this valve is normally held in its closed

position by the spring M which is coiled around the valve stem extension J'. The inner end of the valve plug has formed thereon the valve seat O, and P is a secondary valve adapted to close upon this seat and guided in place by the stem P'. The outer end of the body is threaded as indicated at Q for the reception of the gland nut R which is adapted to force the sleeve S against the packing S' and thus prevent the escape of steam around the stem J.

T represents the hand lever which is pivoted at T' to a suitable bracket T², said bracket being either cast with the body or arranged to be clamped thereto as may best suit the requirements of the particular work the device is intended for.

From the foregoing description the operation of my improvement will be obviously as follows:—The valve stem extension J' being of sufficient length to abut against the valve stem P' the valve P will be normally held off its seat thus permitting the free flow of steam through the nipple and valve plug to the valve L, and as the latter is normally held closed by the spring M no steam can pass this last named valve until it is forced off of its seat, the latter being accomplished by forcing the hand lever inward against the valve stem J thus opening the valve K and permitting the steam to flow into the opening I from whence it will issue through the outlet U. Upon the release of the hand lever the spring M together with the pressure of the steam will close the valve K and cut off the further flow of the steam or water. Should it become necessary to remove the gage cock for repair such as regrinding the valve K and its seat L or for other purposes the screwing off of the body from the valve plug will carry the valve stem extension J' out of contact with the valve stem P' thus permitting the valve P to be forced against its seat by the steam pressure where it will be held thus preventing the outflow of the steam or water, and when the gage cock has been repaired and replaced the valve P will again be forced off its seat and so held again permitting the steam or water to flow to the valve K.

In practice this is of great advantage since it avoids the liability of injury to the attendant and permits the repacking of the valve stem J and the grinding or cleaning of the valve K without permitting the escape of steam.

While I have here shown a portion of the valve stem J and the valve stem P' of tri-

angular shape in cross section it is obvious that they may be of any desired shape. It is also obvious that the valve K may be provided with a fiber washer for seating upon the valve seat L.

Having thus fully described my invention, what I claim as new and useful, is—

A gage cock composed of a three part casting, first a central portion having a bore therethrough and reduced exteriorly threaded ends forming opposite shoulders, second a nipple having one end exteriorly threaded and its opposite end threaded onto one of said ends of the central portion and abutting one of said shoulders thereof, and third a body threaded at one end onto the other end of said central portion and abutting the other

shoulder thereof, said central portion being formed with a valve seat at one end thereof, said body being formed with a valve seat intermediate its ends, and a valve for each of said seats, a stem on each valve having their inner ends abutting, means for operating said stem in the body, and a coil spring engaging the valve in said body at one end and at its opposite end abutting the opposite end of said central portion.

In testimony whereof, I have hereunto affixed my signature in the presence of two subscribing witnesses.

THOMAS WATKINS.
